FUEL BURNER CONTROL

Siegfried G. Isserstedt, Minneapolis, Minn., assignor to Minneapolis-Honeywell Regulator Company, Minneapolis, Minn., a corporation of Delaware

Application March 25, 1942, Serial No. 436,139

16 Claims. (Cl. 158—28)

This invention relates generally to automatic control systems for fluid fuel burners and is more particularly concerned with that type of system which employs a device responsive to the rate of change of the temperature of combustion for the purpose of sensing the appearance or disappearance of a flame at the burner.

In prior art fuel burner control systems which employ a device responsive to combustion, it is usual to employ a device which will assume one position in the presence of combustion and a second position in the absence of combustion. This leads generally to the utilization of hot and cold switches wherein the hot switch is closed upon the establishment of combustion and remains closed until combustion ceases at which time the cold switch is closed, and the cold switch will remain closed until combustion is again established. One of the principal objects of the present invention is to design a system using a different type of combustion responsive device; that is, one which responds to the rate of change of the temperature of combustion, or radiation produced by combustion and which will therefore assume a first position when the temperature of combustion is increasing above a predetermined rate, a second position when the temperature of combustion is decreasing at a rate above a predetermined value. A further object of the invention is to bias the combustion responsive device to a mid or intermediate position which it will assume when the rate of change of combustion is less than some predetermined rate.

A further object of the invention is to provide a control system for use with a combustion responsive device of the above type and arrange this system so that upon the establishment of combustion the combustion responsive device will move to a first position to render the safety switch inoperative to open the control circuit and then terminate ignition as said combustion responsive device returns to its intermediate position, and then prevent operation of the burner motor when the combustion responsive device moves to a second position in response to the disappearance of flame of the burner, and not permit burner operation until said combustion responsive device has returned to its intermediate position.

A further object of the invention is to provide a control system of the above type with a pair of relays having interlocked switching mechanism to provide for the proper operation of the safety switch heater and the ignition device. This switching mechanism is so arranged that one

switch will be closed by the first relay to be energized and will then be opened by the second relay to be energized. Another switch will be closed by the second relay to be energized and will then remain closed until the first relay to be energized has been deenergized.

A still further object of the invention is to provide a first relay with a main operating winding for energizing the burner motor and ignition device and a bucking winding which may be energized by the combustion responsive device upon a subsequent failure of combustion to prevent operation of the burner motor for a predetermined time following the disappearance of the flame at the burner.

These and other objects will readily become apparent to those who are skilled in the art as the following specification is read in the light of the accompanying drawing, in which

20 Figure 1 schematically illustrates a control system for a fuel burner which incorporates the various features of my invention therein.

Figure 2 is a top elevation of the two relays utilized by my control system employing the interlocked switching mechanism.

Figure 3 is a section taken along the lines 3—3 of Figure 2, and

Figure 4 is a detail view of the interlocking mechanism employed in connection with the two relays.

Referring first to Figures 2, 3 and 4, the reference numerals 10 and 11 indicate two electromagnetic relays having armatures 12 and 13 which are biased to their unattracted position by means of the biasing springs 14 and 15. Referring to Figure 3, the reference numeral 16 indicates the base of the relay 11 which carries a coil 17 and core 18. The armature 13 comprises an insulating member 19 which carries an iron plate 21 which is, in turn, pivotally mounted upon the base 16. The biasing spring 15 is shown as biasing the armature 13 for rotation in a counter-clockwise direction. The corresponding portions of the relay 10 are similar in form and therefore have not been shown separately.

The flexible contact blades 24 and 25 are carried by the insulating member 26 of relay 11. The insulating member 26 also carries two pairs of resilient contact blades indicated at 27 and 28 which are alternately bridged by the electrically conducting member 29 which is carried by the armature 13. The arrangement is such that when the relay 11 is energized the bridging member 29 bridges the two blades 28 and when the

relay is deenergized the bridging member 28 bridges the two blades 27. The relay 10 is provided with a stationary insulating portion 32 to which is fixed a bracket 33. Bracket 33 is provided with a pair of ears 34 which pivotally carry the lever 35, which is biased for rotation in a counter-clockwise direction as viewed in Figure 3 by means of the biasing spring 36. The bracket 33 is provided with a second pair of ears 38 which pivotally carry the latch member 39. The right hand portion of the latch member 39 overlies the resilient contact blade 28 as viewed in Figure 4, and this blade biases the latch member for rotation in a counter-clockwise direction in which the projection 46 on the latch member 39 abuts the lever 35 whereas the extension 44 extends directly beneath the lever 35 and latches it in the position shown in Figures 2, 3 and 4.

The relay 10 is also provided with a pair of resilient blades 43 each carrying a contact as seen in Figures 3 and 4. A third contact mounted on the resilient blade 44 is located directly between the two blades 43 and the armature 12 is provided with a bridging member for electrically connecting these three contact blades when the relay is energized. A second pair of stationary contacts are mounted on the resilient blades 45 and the armature 12 carries a second bridging member for bridging these two contact blades when the relay is energized.

An insulating pin 47 is received in the hole shown in dotted lines at 48 in Figure 4 and extends between the resilient contact blade 44 and the pivoted lever 35. With the lever 35 in the position shown in the drawing, the pin 47 is in its retracted position and the contact blade 44 is in a position to be engaged by the bridging member along with the two contact blades 43 when the relay 10 is energized. However, when the latch 39 is rotated in a clockwise direction, and the lever 35 is released, its biasing spring 36 will rotate it in a counter-clockwise direction as seen in Fig. 3 resulting in a depression of pin 47 which will move the resilient blade 44 downwardly and out of contact with the electrical bridging member, thereby opening the switch formed thereby.

The complete operation of the two relays and the interlocked switching mechanism will now be described. The sequence of operation of the two relays, as will be pointed out in more detail in connection with the operation of the system as a whole, is, first the energization of relay 10, second the energization of relay 11, third, the deenergization of the relay 11, and finally the deenergization of the relay 10. Originally, both of the relays will be deenergized and the parts will therefore assume the position shown in Figures 2, 3 and 4. The only switch closed at this time will be the switch formed by the two contact blades 27 and the bridging member 28. The latch member 39 will be in the position shown in Figure 4 in which the lever 35 is locked in its clockwise position at which time the resilient contact blade 44 will be in a position to be engaged by the bridging member of the armature 12 when the relay 10 is energized. Therefore, upon energization of the relay 10 the resilient blades 43 and 44 will be electrically connected as will be the blades 45. Rotation of the lever 35 is prevented by the latch 39. Upon a subsequent energization of the relay 11, the armature 13 will pull in and unbridge the resilient blades 27 and bridge the blades 28. At the same time, the extension 50 on the armature 13 will engage the right hand end of the latch member 39 and depress it causing it to move the

resilient contact blade 28 into engagement with the contact blade 24. At the same time, the latch member 39 will be rotated to release the lever 35 and cause it to be rotated in a counter-clockwise direction by the biasing spring 36 which will result in a depression of the pin 47 and a movement of the resilient blade 44 out of engagement with the bridging member carried by the armature 12. It will be noted that this counter-clockwise rotation of the lever 35 will now lock the latch member 39 in the position to which it has been rotated by the armature 13. Thus, upon a subsequent deenergization of the relay 11, the armature 13 will drop out and unbridge the contact blades 28 and bridge the contact blades 27 again. The latch member 39 will remain locked, however, and therefore, will maintain the resilient blade 28 in engagement with the blade 24. When the relay 10 is deenergized the armature 12 will drop out and unbridge the blades 45 and 43 and will also lift the end 51 of the lever 35 and cause it to rotate in a clockwise direction as seen in Figure 3. This will release the latch member 39 which will permit the resilient contact blade 28 to move upwardly under the influence of its bias and rotate the latch member 39 back to the position shown in Figure 4.

It will thus be seen that the interlocked mechanism between the two relays 10 and 11 provide for closure of the switch formed by the resilient contact blade 44 when the relay 10 is energized and the opening of this switch when the relay 11 is energized. It will be noted further that this switch cannot be reclosed until both the relays 10 and 11 have been deenergized and the relay 10 again energized. It will be noted further that the switch formed by the two resilient contact blades 24 and 28 is closed by energization of the relay 11 and will remain closed until the relay 10 is deenergized, although the relay 11 is deenergized first.

In Figure 1, the two relays have been shown very diagrammatically but the same reference numerals have been used to designate like parts wherever possible. In this figure, the relay 10 has been shown as comprising a main energizing coil 55 and an oppositely wound bucking coil 56. The contact blades 45 and bridging member carried by the armature 12 have been indicated as a stationary contact 45 and a movable switch arm 12b. The two stationary switch blades 43 and associated bridging member have been indicated as a stationary contact 43 and a switch arm 12a. The intermediate resilient switch blade has been indicated at 44 with its actuating pin 47 and the bridging member has again been indicated as the switch arm 12a. In connection with the relay 11, the two switch blades 27 have been indicated as a single stationary contact 27 and the two switch blades 28 have been indicated as a single stationary contact 28, both being engageable by switch arm 28 which, as shown, is indicated as engaging the stationary contact 27 when the relay 11 is deenergized and the contact 28, when the relay is energized. The two switch blades 24 and 28 have been given the same reference numerals, as well as the latch 39 and the projection 50 on the armature 13. The relay 11 is shown as comprising an energizing coil 57.

The combustion responsive device is shown at 60. This combustion responsive device is shown as comprising a three part housing having a front portion 61, a main portion 62, and a switch housing portion 63. The two portions 61 and 62

are hollowed out to form a chamber which contains some suitable gas which expands upon increase in temperature. In the present instance, this gas is air, but it is obvious that various other types of gases, or possibly even liquids may be used. A suitable absorbing member such as a thin sheet of metal foil, blackened on its surface so as to more readily absorb heat rays, is mounted within the gas chamber and has been designated as 84. The front portion 81 of the housing is preferably made of some material which will readily pass radiant heat therethrough to be absorbed by the metal foil 84 to rapidly heat the air within the chamber which is designated at 85. The air chamber 85 communicates with a diaphragm chamber 86 by means of the passage 87, the diaphragm 88 being shown as clamped between the portions 82 and 83 of the housing. The diaphragm 88 is therefore responsive to the pressure within the chamber 85 at one side. It is connected to an actuating stem 89 which extends loosely through the housing 83 as shown at 78. The diaphragm 88 is therefore responsive on the other side to atmospheric pressure.

The switch housing portion 83 supports a first resilient contact blade 72 and a second resilient contact blade 73, both of which are biased against the walls of the housing as shown and hence, out of engagement with their respective stationary contacts 74 and 75. The stem 89 has a switch actuating member 71 fixed thereto and located between the two resilient blades 72 and 73. The two blades therefore, tend to bias the stem 89 to a mid-position in which both of the blades are in open circuit position. The arrangement is such that this corresponds to a mid-position of the diaphragm 88, and this diaphragm may, if desired, be formed of neoprene or some other resilient material which is itself biased to a mid-position in which both of the contact blades 72 and 73 are in open circuit position. The diaphragm 88 and the two blades 72 and 73 will therefore assume the position shown in Figure 1, when the pressures across the diaphragm 88 are substantially equal. The air chamber 85 communicates with the switch housing 83 by means of a restricted opening 78.

The operation of the combustion responsive device 88 should now be apparent. Assuming that the device is so mounted that the radiant heat of combustion will pass through the front portion 81 of the housing and, strike the heat absorbing member 84, it will be clear that upon establishment of combustion the radiant heat will be absorbed and raise the temperature of the air in the chamber 85. This will increase the pressure in this chamber and cause the diaphragm 88 to move upwardly as viewed in Fig. 1, thereby moving the resilient blade 73 into engagement with the stationary contact 75. The increased pressure in the air chamber 85 will cause air to gradually bleed through the restricted opening 78 which will result in this pressure being gradually reduced again to atmospheric at which time the diaphragm 88 will return to its mid-position as shown in Figure 1, and the resilient contact blade 73 will hence be moved to open circuit position. When combustion is terminated at the burner the heat absorbed by the metal foil 84 and the heat in the chamber 85 will be rapidly dissipated with the result that the air will contract and reduce the pressure in the chamber below atmospheric pressure thereby causing the diaphragm 88 to move downwardly as viewed in Figure 1 and cause the resilient con-

tact blade 72 to move into engagement with the stationary contact 74. Air will gradually bleed through the restricted opening 78 into the chamber 85 and return this chamber to atmospheric pressure at which time the diaphragm 88 will return to its mid-position thereby moving the resilient contact blade 72 again to its open circuit position. It will thus be seen that upon the establishment of combustion the switch 73, 75 is closed for a certain period of time depending upon the size of the restricted opening 78 and again upon the cessation of combustion of the burner the switch 72, 74 is closed for a certain period of time which is also dependent upon the size of the restriction 78. Thus, the combustion responsive device 88 responds to the rate of change of the temperature of combustion and this rate may be adjusted by adjusting the size of the restriction 78.

If desired, the switch housing 83 may be entirely enclosed and sealed from the atmosphere and the desired results will be obtained by an equalization of the pressures in the air chamber 85 and in the switch housing 83 through the restricted opening 78. Actually, this is the preferred construction since it prevents dirt from getting at the switch contacts and from getting into the restricted opening 78 and blocking it.

Actually, this control system may be placed under the control of any one of a number of various condition responsive devices, but for the purposes of illustration the condition responsive device has been shown in the form of a room thermostat which comprises a bimetallic member 80 which is fixed at one end and which carries at its free end a resilient contact blade 81 and a second contact blade 82 which cooperate respectively with the two stationary contacts 83 and 84. The arrangement is such that on a decrease in temperature the bimetallic element 80 will contract and cause the resilient contact blade to engage the stationary contact 83 at one temperature, and then at a slightly lower temperature the second contact blade 82 will move into engagement with this stationary contact 84.

Any of the usual forms of thermally actuated safety switches may be used but for the purposes of illustration, the switch is shown as comprising a pair of resilient contact blades 86 and 87 which are biased to open circuit position but which are latched in closed position by means of bimetallic blade 88, which is fixed at its lower end and which engages the resilient blade 87 at its upper end. The blade 88 latches the switch blades 86 and 87 in closed position when cold but when heated to a predetermined temperature by the electric heating element 89, will warp toward the left and release these blades for movement to open circuit position. When the switch has once been open it is effectively locked in open position until it is manually reset by means of the manual reset button 90 which acts to hold the switch in open circuit position during resetting operation so that under no circumstances can this switch be held closed manually. In other words, this switch is provided with a trip-free manual reset.

It will be readily understood that various types of fuel burners may be controlled by this system, but for purposes of illustration, it has been shown as controlling the usual oil burner motor 91 and ignition device 92 for igniting the oil. The electrical power for operating the system is provided by the two supply lines 93 and 94 to which the primary winding 95 of the step-down transformer 96 is connected by means of the conductors 97

and 88. The transformer 96 is provided with the usual secondary winding 98 for supplying power to the low voltage portion of the system.

Operation

In Figure 1, the thermostat 80 has been shown in a satisfied condition in which its switches are in open circuit position and the two relays 10 and 11 are therefore deenergized. This means that the burner motor 91 and ignition device 92 are deenergized and therefore, there is no combustion present at the burner. The diaphragm 68 of the combustion responsive device is in its mid-position and its two contact blades 12 and 13 are therefore in open circuit position. The movable switch member 29 of the relay 11 is in engagement with its out contact 27 but the circuit in which this switch is located is open because the switch member 12a of the relay 10 is in open circuit position.

The temperature at the thermostat 80 will therefore begin to decrease which will first cause the thermostat to move the resilient contact blade 81 into engagement with the stationary contact 83. This will not establish a circuit at this time, due to the fact that the switch arm 12b of the relay 10 is in open circuit position. The temperature will continue therefore to decrease until the thermostat 80 causes the switch blade 82 to engage the stationary contact 84. This will establish a circuit from one side of the secondary winding 98 through conductor 100, electric heater 89 for the safety switch blade 88, conductor 101, safety switch blades 86 and 87, conductor 102, contact 83, switch blades 81 and 82, contact 84, conductor 103, main energizing winding 55 of the relay 10, conductors 104, 105 and 106 back to the other side of the secondary winding 98. This causes energization of the relay 10 and the movement of the armature 12 to its attracted position which causes the switch arm 12b to engage contacts 43 and 44. Engagement of the switch arm 12b with contact 45 establishes a holding circuit through the thermostat 80 which passes directly from contact 83, resilient switch blade 81, bimetallic element 80, conductor 107, switch arm 12b, contact 45, and conductor 108 directly to the energizing winding 55 of the relay 10. This circuit is independent of the switch blade 82 and contacts 84, and therefore, the winding 55 will remain energized until the resilient switch blade 81 is moved out of engagement with the stationary contact 83. Movement of the switch arm 12a into engagement with the stationary contact 43 energizes the burner motor 91 by means of a circuit extending from the line wire 93 through conductor 110, burner motor 91, conductor 111, switch arm 12a, contact 43 and conductor 112 back to the other line wire 94. Movement of the switch arm 12a into engagement with the contact 44 energizes the ignition device by means of a circuit extending from the line wire 93 through conductor 113, ignition device 92, conductor 114, switch arm 29, out contact 27, conductor 115, switch blade 44, switch arm 12a, conductor 116, switch arm 12a, contact 43 and conductor 112 back to the other line wire 94.

It will thus be seen, that upon a call for heat by the thermostat 80, the burner motor and ignition device will be simultaneously energized. It will be seen also that the electric heater 89 for the safety switch is in the energizing circuit and holding circuit for the energizing winding 55 of the relay 10 so that if this electric heater re-

mains energized for a predetermined period of time this will cause the blade 88 to warp to the left and release the safety switch blade 87 for movement to open circuit position. This will deenergize the relay 10 and therefore, deenergize the burner motor 91 and ignition device 92. The system is then effectively locked out until the safety switch is reset by means of the manual reset button 86.

10 Normally however, combustion will be established which will cause the air in the chamber 65 to expand and move the diaphragm 68 in a direction to cause engagement between the resilient contact blade 13 and the stationary contact 15. This will establish a circuit from one side of the secondary winding 98 through conductor 100, safety switch heater 89, conductor 101, safety switch blades 86 and 87, conductor 102, contact 83, resilient blade 81, bimetallic element 80, conductor 107, switch arm 12b, contact 20 45, conductors 108 and 120, resilient contact blade 13, contact 15, conductor 121, winding 17 of the relay 11, and conductors 122 and 108 back to the other side of the secondary winding 98. The establishment of this circuit, therefore, results in the energization of the relay 11 with a resultant movement of the switch arm 29 out of engagement with contact 27 and into engagement with contact 28. This sets up a new circuit for the 25 ignition device which extends from the line wire 93 through conductor 118, ignition device 92, conductor 114, switch arm 29, contact 28 and conductor 123 back to the other supply line 94. At the same time, the armature 13 of the relay 11 30 rotates the latch member 38 in a direction to release the lever 35 which rotates in a direction to lower the pin 41 as seen in Fig. 4, or to raise this pin as seen in Figure 1, to move the resilient contact blade 44 to open circuit position. This 35 resilient contact blade, it will be remembered, was in the original energizing circuit for the ignition device 92.

The extension 56 on the armature 13 in rotating the latch 38, also moves the resilient contact blade 25 into engagement with the contact blade 24. This establishes a shunt circuit around the safety switch heater 89 which effectively deenergizes it. This circuit comprises the conductor 128, switch blades 24 and 25, and conductor 126. 40 It will be recalled that the latch 38 in releasing the lever 35 locks itself in the position to which it is moved by the armature 13 and therefore, effectively locks the switch blades 24 and 25 in closed circuit position. These switch blades will 45 remain in closed circuit position until the relay 10 is deenergized to raise the lever 35 and release the latch member 38.

After a predetermined time interval, the pressure across the diaphragm 68 will be equalized due to the restricted opening 78, thus causing a return of the diaphragm 68 to its mid-position and a return of the resilient contact blade 13 to open circuit position. Such action deenergizes the winding 17 for the relay 11 and this relay drops out causing the switch arm 29 to move out of engagement with contact 28 and into engagement with contact 27. This deenergizes the ignition device because the resilient contact blade 44 has now been moved to open circuit position. 50 As set forth above, the resilient contact blades 24 and 25 remain in closed circuit position and therefore, the safety switch heater 89 remains deenergized. This is the running condition of the system.

75 One of the advantages of this system may be

noted at this point, and that is that the ignition device is not deenergized immediately upon the establishment of combustion, whereas the safety switch heater 88 is deenergized immediately upon establishment of combustion. More specifically, it is the engagement of the contacts 18 and 78 which results in the energization of the relay 11 and the deenergization of the safety switch heater 88, whereas the ignition device is not deenergized until the pressures across the diaphragm 68 have been equalized through the restriction 78 resulting in the opening of the switch 18, 78. This timing can obviously be adjusted by adjusting the size of the restriction 78 or the position of contact 78. It will be noted that although the energization of the relay 11 caused the opening of the switch 44, the deenergization of this relay will not result in the reclosure of this switch due to the fact that the lever 35 remains in its tripped position in which it causes the stem 47 to depress the switch blade 44. This blade will remain in open circuit position until the relay 10 has first been deenergized and then reenergized. The system will remain in this condition as long as combustion remains at the burner and as long as the thermostat 80 continues to call for heat.

When the thermostat 80 becomes satisfied it will move the resilient contact blade 81 out of engagement with the stationary contact 83 and therefore, deenergize the energizing winding 55 of the relay 10. This will result in a deenergization of the burner motor 81. Deenergization of the relay 10 will also reset the lever 35 upon the latch member 38, thereby permitting the switch 24, 25 to move to open circuit position and also permitting the resilient blade 44 to move to a position where it will again be engaged by the switch arm 12a and the relay 10 is again energized. The resultant cessation of combustion at the burner will cause the air within the chamber 65 to contract and lower the pressure therein and the diaphragm 68 will therefore move downwardly and cause the resilient contact blade 12 to engage stationary contact 74. Although this switch is in circuit with the bucking winding 56, this winding will not be energized at this time due to the fact that the circuit will be open at the thermostat 80. However, should the circuit at the thermostat 80 be reclosed before the pressures have equalized across the diaphragm 68, the relay 10 could not be energized due to the fact that both the energized winding 55 and the bucking winding 56 would both be energized. The energizing circuit for the winding 55 would be the same as traced above in connection with the original energization of the circuit. The circuit for the bucking winding 56 extends from one side of the secondary winding 98 through conductor 100, safety switch heater 88, conductor 101, safety switch blades 86 and 87, conductor 102, contact 83, switch blades 81 and 82, contact 84, conductor 103, conductor 120, conductor 128, resilient switch blade 72, contact 74, conductor 129, bucking winding 56, and conductors 130, 105 and 106 back to the other side of the secondary winding 98. It will thus be seen that once the burner motor 81 has been deenergized by the thermostat 80, or for that matter due to a momentary power failure, and then the circuit reclosed immediately it will be impossible for the burner motor 81 to be reenergized until the pressures across the diaphragm 68 have had a chance to equalize following the change in pressure in the air chamber 65 caused by cessation of com-

bustion at the burner. In other words, the combustion responsive device 66 with its restriction 78 provides for the proper recycle timing of the system.

In the event that the system should be operating normally and a flame failure should occur, the air in the chamber 65 would immediately contract and reduce the pressure therein, thus causing the resilient blade 72 to engage the contact 74. This would result in the energization of the bucking winding 56 by means of the circuit just traced above with the result that the relay 10 would drop out and deenergize the burner motor 81. The relay 10 would remain deenergized until the pressures across the diaphragm 68 have equalized and caused the resilient contact blade 12 to return to open circuit position. During all this time, the energizing winding 55 would remain energized. The relay 10 would then pull in and reenergize the burner motor 81 and ignition device 82 and the system would attempt to start normally. If combustion was not established then the safety switch heater 88 would cause the safety switch to open and lock the system out until the trouble was corrected and the system manually reset.

As many changes and modifications of this invention will undoubtedly occur to those who are skilled in the art, I wish it to be understood that I intend to be limited only by the scope of the appended claims and not by the specific embodiment of the invention which has been disclosed herein merely for the purposes of illustration.

I claim as my invention:

1. A fluid fuel burner control system comprising in combination, means including an electric device in control of the delivery of fuel to a burner, a device responsive to the rate of change of the temperature of combustion, means including a relay for energizing said electric device, said relay having a main winding and a bucking winding, a main switch closed in response to a demand for burner operation, an energizing circuit for said relay including said main switch and main winding, and a normally open cold switch closed by said combustion responsive device when the temperature of combustion decreases above a predetermined rate, and means controlled by said cold switch for connecting said bucking winding in parallel with said main winding whereby said relay will be effectively deenergized regardless of whether said main switch is open or closed.

2. A fluid fuel burner control system comprising in combination, means including an electric device in control of the delivery of fuel to a burner, a device responsive to the rate of change of the temperature of combustion, a normally closed, thermally open safety switch in control of said electric device, a heater for said safety switch, means including a condition responsive device for simultaneously energizing said electric device and heater upon a demand for burner operation, means operated by said combustion responsive device for deenergizing said heater when the heat of combustion increases above a predetermined rate, a normally open cold switch closed by said combustion responsive device when the temperature of combustion decreases above a predetermined rate, and means controlled by said cold switch for preventing energizing of said electric device as long as said cold switch is closed.

3. A fluid fuel burner control system comprising in combination, means including an electric device in control of the delivery of fuel to a burner, a device responsive to the rate of change of

the temperature of combustion, a normally closed, thermally open safety switch in control of said electric device, a heater for said safety switch, means including a relay for energizing said electric device, said relay having a main winding and a bucking winding, a main switch closed in response to a demand for burner operation, an energizing circuit for said relay including said main switch, main winding and heater, means operated by said combustion responsive device for deenergizing said heater when the heat of combustion increases above a predetermined rate, and a normally open cold switch closed by said combustion responsive device when the temperature of combustion decreases above a predetermined rate, means controlled by said cold switch connecting said bucking winding in parallel with said main winding whereby said relay will be effectively deenergized regardless of whether said main switch is open or closed.

4. A fluid fuel burner control system comprising in combination, means including an electric device in control of the delivery of fuel to a burner, a device responsive to the rate of change of the temperature of combustion, a normally closed, thermally open safety switch in control of said electric device, a heater for said safety switch, means including a relay for energizing said electric device, said relay having a main winding and a bucking winding, a main switch closed in response to a demand for burner operation, an energizing circuit for said relay including said main switch, main winding and heater, a second relay, a normally open hot switch closed by said combustion responsive device when the temperature of combustion increases above a predetermined rate, means including said hot switch for energizing said second relay when energized for deenergizing the heater for said safety switch, and a normally open cold switch closed by said combustion responsive device when the temperature of combustion decreases above a predetermined rate, means controlled by said cold switch connecting said bucking winding in parallel with said main winding whereby said relay will be effectively deenergized regardless of whether said main switch is open or closed.

5. A fluid fuel burner control system comprising in combination, means including an electric device in control of the delivery of fuel to a burner, a device responsive to the rate of change of the temperature of combustion, a normally closed, thermally open safety switch in control of said electric device, a heater for said safety switch, means including a relay for energizing said electric device, said relay having a main winding and a bucking winding, a main switch closed in response to a demand for burner operation, an energizing circuit for said relay including said main switch, main winding and heater, a second relay, a normally open hot switch closed by said combustion responsive device when the temperature of combustion increases above a predetermined rate, means including said hot switch for energizing said second relay when energized for deenergizing the heater for said safety switch, means controlled by said first relay for maintaining said heater deenergized, once it has been deenergized by said second relay, until said first relay has been deenergized and the energizing circuit therefor reclosed, and a normally open cold switch closed by said combustion responsive device when the temperature of combustion decreases above a prede-

termined rate, means controlled by said cold switch for connecting said bucking winding in parallel with said main winding whereby said relay will be effectively deenergized regardless of whether said main switch is open or closed.

6. A fluid fuel burner control system comprising in combination, means including an electric device in control of the delivery of fuel to a burner, a device responsive to the rate of change of the temperature of combustion, a normally closed, thermally open safety switch in control of said electric device, a heater for said safety switch, means including a first relay for energizing said electric device, a main switch closed in response to a demand for burner operation, an energizing circuit for said relay including said main switch and heater, a second relay, a hot switch closed by said combustion switch while the temperature of combustion is increasing above a predetermined rate, an energizing circuit for said second relay including said hot switch, and means controlled by said first relay for maintaining said heater deenergized, once it has been deenergized by said second relay, until said first relay has been deenergized and the energizing circuit therefor reclosed.

7. A fluid fuel burner control system comprising in combination, means including an electric device in control of the delivery of fuel to a burner, a device responsive to the rate of change of the temperature of combustion, a normally closed, thermally open safety switch in control of said electric device, a heater for said safety switch, means including a first relay for energizing said electric device, a main switch closed in response to a demand for burner operation, an energizing circuit for said relay including said main switch and heater, a second relay, a hot switch closed by said combustion switch while the temperature of combustion is increasing above a predetermined rate, an energizing circuit for said second relay including said hot switch, a heater switch, means including said heater switch effective when said heater switch is closed to establish a shunt circuit around said heater for effectively deenergizing it, means operated by said second relay, when energized for closing said heater switch and latching it closed, and means operated by said first relay, when deenergized, for tripping said latch to permit said heater switch to move to open position.

8. A fluid fuel burner control system comprising in combination, means including an electric device in control of the delivery of fuel to a burner, means for igniting said fuel, a main switch closed in response to a demand for burner operation, a circuit for simultaneously energizing said electric device and igniting means, said circuit including said main switch, means movable in response to the rate of change of the temperature of combustion, said last mentioned means normally occupying a first position, said means moving to a second position while the rate of change is above a predetermined value incident to the establishment of combustion and returning to its first position as said rate of change approaches zero, and means operated by said combustion responsive means as it returns to its first position for deenergizing said igniting means.

9. A fluid fuel burner control system comprising in combination, means including an electric device in control of the delivery of fuel to a burner, means for igniting said fuel, a main

switch closed in response to a demand for burner operation, a first relay for simultaneously energizing said electric device and establishing a first circuit to said igniting means for energizing the same, an energizing circuit for said first relay including said main switch, a hot switch, means for closing said hot switch in response to the increase of the temperature of combustion above a predetermined rate incident to the establishment of combustion and opening said hot switch again as said rate of increase approaches zero, a second relay, an energizing circuit therefor including said hot switch, and means operated by said second relay when energized for opening said first circuit to said igniting means and establishing a second circuit therefor, means operated by said second relay, upon deenergization thereof, for opening the second circuit to said igniting means to deenergize the same.

10. A fluid fuel burner control system comprising in combination, means including an electric device in control of the delivery of fuel to a burner, means for igniting said fuel, a main switch closed in response to a demand for burner operation, a first circuit for said igniting means, a first ignition switch in said circuit, an energizing circuit for said first relay including said main switch, said relay when energized causing energization of said electrical device and closure of said first ignition switch to energize said igniting means, a second relay, a hot switch, means for closing said hot switch in response to the increase in the temperature of combustion above a predetermined rate incident to the establishment of combustion and opening said hot switch again as said rate of increase approaches zero, an energizing circuit for said second relay including said hot switch, a second circuit for said igniting means, a second ignition switch in said last named circuit, means operated by said second relay when energized for opening said first ignition switch and closing said second ignition switch to maintain energization of said igniting means, means operated by said second relay, when deenergized, for opening said second ignition switch, and means controlled by said first relay to prevent reclosure of said first ignition switch until after said first relay has been deenergized and then energized again.

11. An automatic control system for fluid fuel burners comprising in combination, means including an electric device in control of the flow of fuel to a burner, means for igniting said fuel, a safety switch in control of said electric device and igniting means, a thermal actuator for said safety switch, a heater for said thermal actuator, a condition responsive device simultaneously energizing said electric device, igniting means and heater upon a demand for burner operation, means responsive to the rate of change of the temperature of combustion, and means actuated thereby upon an increase in said rate of change indicating the establishment of combustion for deenergizing the heater for said safety switch, means including said last mentioned means operating to deenergize said igniting means upon a subsequent decrease in said rate of change.

12. A fluid fuel burner control system comprising in combination, means including an electric device in control of the delivery of fuel to a burner, means for igniting said fuel, a main switch closed in response to a demand for burner operation, a thermally actuated safety switch in control of said electric device and igniting means, a heater for said safety switch, a first relay for

simultaneously energizing said electric device and igniting means, an energizing circuit for said first relay including said main switch and heater, a second relay, a hot switch, means for closing said hot switch in response to an increase in the temperature of combustion above a predetermined rate and opening said hot switch as said rate again approaches zero, an energizing circuit for said second relay including said hot switch, a heater switch, means including said heater switch effective when said heater switch is closed to establish a shunt circuit around said heater for effectively deenergizing it, means operated by said second relay, when energized, for closing said heater switch and latching it closed, and means operated by said first relay, when deenergized, for tripping said latch to permit said heater switch to move to open position.

13. A fluid fuel burner control system comprising in combination, means including an electric device in control of the delivery of fuel to a burner, means for igniting said fuel, a main switch closed in response to a demand for burner operation, a thermally actuated safety switch in control of said electric device and igniting means, a heater for said safety switch, a first circuit for said igniting means, a first ignition switch in said circuit, an energizing circuit for said first relay including said main switch and heater, said first relay, when energized, simultaneously energizing said electric device and closing said first ignition switch for energizing said igniting means, a second relay, a hot switch, means for closing said hot switch in response to the increase in the temperature of combustion above a predetermined rate incident to the establishment of combustion and opening said hot switch again as said rate of increase approaches zero, an energizing circuit for said second relay including said hot switch, a heater switch, means including said heater switch effective when said heater switch is closed to establish a shunt around said heater for effectively deenergizing it, said second relay, when energized, closing said heater switch and latching it closed, a second ignition switch in a second circuit to said igniting means, means operated by said second relay, when energized, for opening said first ignition switch and closing said second ignition switch to maintain energization of said igniting means, means operated by said second relay, upon deenergization thereof, for opening said second ignition switch to deenergize said igniting means, and means operated by said first relay, upon deenergization thereof for tripping said heater switch to permit opening thereof.

14. A fluid fuel burner control system comprising in combination, means including an electric device in control of the flow of fuel to the burner, hot and cold combustion switches both biased to their open position, means responsive to the direction and rate of change of combustion chamber temperature for closing said hot switch while the combustion chamber temperature is rising and for closing said cold switch while the combustion chamber temperature is falling, a first relay in control of said electric device, a main switch for energizing said first relay and hence said electric device in response to a demand for burner operation, means for igniting the fuel delivered to the burner, means operated by said first relay for rendering said igniting means operative, means including timing means for deenergizing said electric device and igniting means after a predetermined period of time, a

second relay, means including said hot switch for energizing said second relay providing said hot switch is closed before the elapse of said predetermined time, means operated by said second relay upon being energized for rendering said timing means inoperative, means operated by said second relay, as it is deenergized by the subsequent opening of said hot switch, for deenergizing said igniting means, and means operated by said cold switch, upon a subsequent failure of combustion, for deenergizing said first relay and hence said electric device.

15. Fluid fuel burner control apparatus for use with a fluid fuel burner having means for controlling the flow of fuel thereto and with a main switch which is closed upon a demand for operation of said burner, said control apparatus comprising an electric device adapted to be connected to said flow controlling means for causing operation of the latter whenever said device is energized, a device adapted to be exposed to the temperature of the combustion chamber in which said burner is located and responsive when so exposed to the rate of change of the temperature of combustion, a normally open cold switch closed by said combustion responsive device when the latter is subjected to a decrease in the temperature of combustion above a predetermined rate, means adapted to be connected to said main switch for causing energization of said electric device upon closure of said main switch, and means

controlled by said cold switch for preventing energization of said electric device as long as said cold switch is closed.

16. Fluid fuel burner control apparatus for use with a fluid fuel burner having means for controlling the flow of fuel thereto and with a main switch which is closed upon a demand for operation of said burner, said control apparatus comprising an electric device adapted to be connected to said flow controlling means for causing operation of the latter whenever said device is energized, hot and cold combustion switches both biased to their open position, means adapted to be exposed to the temperature of the combustion chamber in which said burner is located and effective when so exposed to close said hot switch while the combustion chamber temperature is rising and to close said cold switch while the combustion chamber temperature is falling, circuit elements connected to said electric device and adapted to be connected to said main switch in such a manner that when said main switch is closed said electric device is energized, means including timing means for deenergizing said electric device at the end of a predetermined time interval, means controlled by said hot switch for disabling said timing means, and means operated by said cold switch for deenergizing said electric device independently of said main switch.
